Primary Examiner — Darcey E Gottschalk(74) *Attorney, Agent, or Firm* — Cislo & Thomas, LLP(57) **CLAIM**

The ornamental design for an egg carton lid, as shown and described.

DESCRIPTION

FIG. 1 is a bottom perspective view of my egg carton lid;
 FIG. 2 is a top perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.

The broken line portions of the disclosure form no part of the claimed design.
